UNITED STATES PATENT OFFICE.

CHARLES M. LANCASTER, OF TRAVERSE CITY, MICHIGAN.

PACKAGE-TIE.

No. 902,091.

Specification of Letters Patent.

Patented Oct. 27, 1908.

Application filed October 9, 1907. Serial No. 396,648.

To all whom it may concern:

Be it known that I, CHARLES M. LANCASTER, a citizen of the United States, residing at Traverse City, in the county of Grand 5 Traverse and State of Michigan, have invented a new and useful Package-Tie, of which the following is a specification.

This invention relates generally to package ties, and more particularly to that class 10 designed for use by the Post Office Department in its railway mail service for holding various kinds of mail matter securely assembled.

The object of the invention is to provide 15 an article of this character which shall be simple and durable of construction, easy to manipulate, in the use of which the binder shall be so secured around a package of mail matter or the like that its accidental loosening or untying will be practically impossible, and in which cutting of the binder will positively be prevented.

With the above and other objects in view, as will appear as the nature of the invention 25 is better understood, the same consists in the novel construction and combination of parts, of a mail package tie, as will be hereinafter fully described and claimed.

In the accompanying drawings, forming 30 a part of this specification, and which like characters of reference indicate corresponding parts:—Figure 1 is a view in plan, partly in section, showing the manner in which the tie is assembled with a package of 35 mail matter or the like. Fig. 2 is a view in vertical longitudinal section through the tie. Fig. 3 is a top plan view. Fig. 4 is a view similar to Fig. 2 displaying the manner in which the binder is disposed when the device is secured around the bundle.

The tie comprises a pair of dished or concaved disks 1 and 2 that are connected at their centers by a binder receiving eyelet 3, the ends of which are upset against the 45 outer faces of the two disks, in any preferred manner. These disks will be made of sheet metal, of any preferred character, preferably one that is non-oxidizable, and

for general purposes of utility sheet tin may be employed.

The binder 4 may be of cord of any preferred character and is held within the eyelet by having its ends knotted. The walls of the eyelet will, by preference, be rounded, so that there will be no danger of the cord 55 being cut thereby.

As will be noted by reference to Fig. 4, the orifices in the disks through which the eyelet projects are of somewhat greater diameter than the eyelet, and further, that 60 there is a suitable space between the opposed faces of the disks. The object of the first arrangement is to permit the disks to rock upon and slide longitudinally of the eyelet, thus to adjust themselves to the binder, and 65 that of the second arrangement is to provide sufficient space between the disks to allow the use of a relatively heavy cord as a binder.

It will be seen that by employing the two 70 disks, that a continuous locking crotch is provided for the binder, so that in positioning the latter around the package of mail matter, no care need be observed where it is inserted within the crotch, for the reason 75 that all parts of the latter are equally effective for engaging and locking the cord, and, furthermore, the cord may be drawn outward at any angle desired, thus to facilitate the tying of different shaped mail packages.

In the use of the tie, the package of letters is grasped in the left hand with the address side down, and the plate or lock is placed upon the back of the package with the 85 binder beneath the same. The operator then passes the binder around and lengthwise of the package to the back thereof, then pinches it in the crotch, then passes the cord transversely around the package to the back, 90 the thumb being still pressed upon the lock, and then again forced into the crotch by which it is securely locked. The binder is removed simply by releasing it from engagement with the lock.

It will be seen from the foregoing descrip-

tion that although the improvements herein defined are simple in character, that they will coöperate in the production of a thoroughly efficient device, and one that will be reliable for the purposes had in view.

5 I claim:—

A package tie, comprising a pair of concave disks with their convex sides opposite each other, and an eyelet connecting said

disks, and on which they are spaced apart, 10 and slidably mounted, and adapted to rock.

In testimony that I claim the foregoing as my own, I have hereto affixed my signature in the presence of two witnesses.

CHARLES M. LANCASTER.
